WELL PUMP

Harold R. Downs, Tulsa, Okla.

Application February 16, 1940, Serial No. 319,341

8 Claims. (Cl. 103—5)

This invention relates to improvements in a fluid operated deep well pump, and more particularly, but not by way of limitation, to means for intermittently admitting the discharge of the actuating fluid for the pump into the eduction tube of the well. This application is a continuation in part of my co-pending application Serial No. 263,022, filed March 20, 1939.

In the particular embodiment shown in my co-pending application supra, a bottom hole rotary pump is driven by a fluid actuated rotary motor to which the actuating fluid, such as gas or air, is automatically controlled by a metering or regulating device. The metering device maintains a pressure differential across the rotary motor sufficient to operate the pump at maximum speed regardless of any variance in pump load. This is accomplished by the cooperation of the motor input and discharge fluid pressures with a plurality of floating pistons regulating an input orifice. The motor discharge fluid in addition is injected into the flow line from the rotary pump to assist the work of the pump by "gas lifting" the fluid load.

In the "aerating" or gas lifting of oil from an oil well, normally a fluid such as gas or air is injected in a vertical column of liquid at or near the base of the liquid, and at a pressure somewhat exceeding the static pressure at the point of injection, and in sufficient volume to cause an upward movement of the fluids in the column. With the gas reaching higher levels in the column or the eduction tube, a gradual expansion of the gas takes place to create a constantly increasing ratio of gas to oil. Injected gas under normal conditions is relatively constant, and the speed of the gas and liquid in the eduction tube will increase until an area of constant pressure (such as atmosphere) is reached, or the friction of the liquid against the walls of the eduction tube will inhibit further increase in speed. Recovery of oil from wells by aerating can be maintained provided the up-rushing and expanding gas does not entirely free itself from the liquid during its upward travel in the eduction tube.

Gas introduced at the base of a column of liquid at a given pressure and through a definite orifice establishes a definite volume of input gas entering the column of oil. This volume of gas at its input pressure will raise the surface of the oil in the column, and, since the gas constantly expands upon reaching higher levels, will extend the column of oil by its original input volume times the ratio of expansion.

It has been found that bubbles of air or gas

rising through a liquid are required to expend a definite amount of energy to force their way to the surface, or conversely, a liquid in a column expends an amount of energy when it frees itself of entrapped air or gas bubbles by a process of the heavier gravity liquid displacing the lighter gas.

In pneumatically aerating a column of oil, the larger bubbles of gas rise quickly and the small bubbles more slowly so that in highly viscous liquids, such as crude oil, it has been found that bubbles of definite size may be arrested. In view of this, air or gas injected into an eduction tube for lifting a column of liquid will expend its compressed energy more effectively if the volume of gas enters the liquid in the greatest number of bubbles possible. In other words, if the gas enters the liquid in such a manner as to create the greatest amount of molecular film or surface tension in the liquid with relation to its volume, the greatest amount of energy will be expended by the gas and the liquid in the process of separation. It is thus apparent that in an oil well to be produced by "gas lift" a thorough breaking up of the oil mass into finely divided gas and oil particles by means of turbulence or agitation will cause an infinite number of bubbles to continuously displace the oil and move upward, thereby allowing the gas and oil mixture to be lifted in the eduction tube at a lower gas speed due to the original volume of compressed gas injected, and also to expansion of the gas. Furthermore, the greatly increased area of the "frothy" gas and oil acts as an impedance to gas flow, as compared to larger bubbles of oil (of greater weight in relation to the surface area) having less resistance to the lifting energy of the gas stream.

In a gas driven motor actuating a fluid pump of the type disclosed in my co-pending application mentioned supra, the discharge gas from the actuating motor is utilized to assist the pump in lifting the column load, and thus obtain the greatest lift efficiency in producing oil from a well hole. By injecting the discharge gas of the motor into the fluid stream in such a manner as to thoroughly agitate and provide a foamy or frothy gas and oil mixture, the column load is substantially lightened. However, the speed at which the discharge gas from the motor is injected into the eduction tube must be given consideration since the pump will produce a pressure head of oil at the point of injection, and if the volume of gas and its speed of flow into the eduction tube is to be maintained, a sufficient pressure differential across the gas driven motor must

be maintained. As disclosed in my co-pending application, the constant pressure differential for the motor for any varying pump load is accomplished by the fluid regulator or metering device where input gas pressure is metered to the motor in relation to a discharge pressure from the motor so as to supply the necessary torque to the rotary pump shaft at any load variation. The maintaining of an unlimited higher input gas pressure above the motor to meet the demands of the metering device, as to pressure differential, assists in controlling the volume and speed of the motor discharge gas entering the eduction tube regardless of the pressure head in the eduction tube.

It is therefore an important object of this invention to increase the lifting efficiency of a bottom hole pump by injecting the discharge fluid from a fluid motor actuating the pump into an eduction tube in such a manner as to cause an infinite number of gas bubbles to continuously displace the pumped liquid slowly upward, due partly to the original volume of gas injected, and partly to the increasing volume of gas during its expansion in vertical travel upward in the eduction tube.

A further object of this invention is to produce liquid from deep wells wherein the weight of the column of liquid is decreased by maintaining pressured gas in an intermingled or occluded state in the liquid.

And still an additional object of this invention is to produce a stream of "frothy" oil and gas from an oil well by introducing the discharge gas of a motor for a rotary pump through a multitude of small apertures so as to thoroughly agitate or "batch" the gas and oil and thus effect a greater lifting efficiency of the column of oil.

And still a further object of this invention is to lift a column of oil by directing a stream of high pressured gas into the column through an orifice which can be alternately opened and closed so that the gas will be intermittently injected into the column of liquid to efficiently foam or "froth" the liquid column and thus lighten the column load.

And still a further object of this invention is to efficiently gas-lift a column of oil by lightening the column load through an intermingling or "batching" of pressured gas with the oil in such a manner that the gas discharges through a multiple apertured orifice at a speed many times greater than that of the oil travel, and at a pressure slightly in excess of the oil at the point of gas discharge.

And another object of this invention is to assist a fluid operated pump in lifting a column of oil from a well hole by directing a stream of high pressured gas actuating the pump into the column so that the gas contacts the oil and causes it to form a frothy mixture of gas and oil before the gas loses a considerable percentage of its density or expands to a lower pressure range.

And a further object of this invention is to produce oil from a well hole by discharging high pressure gas into intimate contact with a stream of oil being pumped in an eduction tube to form a frothy mixture of gas and oil presenting the greatest "wetted area" of oil, which shall prevail from the bottom to the top of the eduction tube.

And another object of this invention is to produce oil from a well hole by injecting dis-

charge gas from a fluid motor actuating a fluid pump into the stream of oil being pumped so that a proper ratio of gas and oil can be established to deliver the gas freed by a surface separator in a state of ultimate oil saturation.

And still another object of this invention is to direct a stream of high pressured gas into a column of oil in such a manner as to cause foaming of the oil whereby continuous flow of gas through the frothy or emulsified oil will provide a decreased flowing pressure to allow natural gasoline absorption of gas or the absorption of lighter hydrocarbons from the oil by the gas.

Other objects and advantages of the invention will be evident from the following detailed description read in conjunction with the accompanying drawings which illustrate one form of my invention.

In the drawings:

Fig. 1 is a vertical elevational view of the invention shown supported in the tubing of a well hole.

Fig. 2 is an enlarged fragmentary sectional elevation of the pump unit showing parts of the motor and rotary pump.

Fig. 3 is a sectional elevational view of the unit taken at a point below the motor, and showing the valve means as taken on lines 3—3 of Fig. 4.

Fig. 4 is a view taken on lines 4—4 of Fig. 3.

Fig. 5 is a detail view showing the outlet orifices for the gas and oil taken on lines 5—5 of Fig. 3.

Fig. 6 is a sectional elevational view of a modified form of the unit showing the uppermost portion of the pump housing to include a plurality of apertures.

Fig. 7 is a view similar to Fig. 3 showing a modified form of construction with the valve unit omitted.

Referring to the drawings in detail and more particularly to Figs. 1, 2 and 3, the pump unit is shown disposed in a well hole provided with a casing 2 and a string of tubing 4. The lowermost section of the tubing 4 is of special construction having an enlarged portion 6 formed at its lower end with an annular projection 8 for receiving an annular ring or gasket 10 upon which the pump cylinder or housing 12 is supported. The pump mechanism proper is contained within the housing 12 and comprises three units, a control regulator or metering device (not shown), the fluid driven rotary motor and the pump unit proper, which are described in detail in my co-pending application mentioned supra.

The uppermost portion of the pump housing 12 is provided with an anchor 14 for facilitating removal of the unit from the well hole. In proximity of the anchor the housing is provided with a plurality of apertures 16 through which input fluid under pressure, such as gas or air, is directed through tubing 4, from a source or supply such as a compressor or the like, at the surface of the well (not shown). The fluid is directed into an inner cylinder 18 welded at 20 to the inner periphery of the housing 12, hence downward into a dual channel or conduit 22 communicating with an apertured block or manifold 24 having its interior forming a conduit 26. The block 24 is threaded to a lower manifold 28 in which is disposed a spring urged ball check valve 30. A cylindrical conduit 32 extends from the manifold 28 into communication with the

regulator or metering device of the unit (not shown), but disclosed in my co-pending application mentioned supra.

A rotary motor is disposed below the fluid regulator and comprises a vertically disposed rotatable shaft 34 journaled in suitable bearings 36 (the upper bearings are not shown, see Fig. 3) secured within the pump housing 12. The shaft 34 is provided with a plurality of radially extending motor vanes 38 adapted to be actuated by the input fluid as to be hereinafter set forth. As shown in Fig. 3, the motor shaft 34 is connected by a suitable coupling 40 with a flexible pump shaft 42, which in turn drives the pump rotor 44, moving in an eccentric path with a stator 46 of the pump. The pump is described in detail in my copending application and is of a construction similar to a patent granted to Moineau, No. 1,802,217, and the novelty of this invention is not limited to this particular structure, it being understood that any suitable type of rotary pump for displacing fluid could be utilized in lieu of the particular structure shown.

Referring to Fig. 3, the shaft 34 is shown extending through an apertured bearing block 48 disposed in the housing 12 below the motor vanes 38. Packing 50 surrounds the shaft 34 and is held in the apertured block by a packing nut 52. Immediately below the block 48 is a valve unit 54 secured by the pin 56 to the shaft 34 so as to be rotated simultaneously with the shaft as will be hereinafter set forth. The lower end of the motor shaft 34, the pump shaft 42, and the valve unit 54 are disposed in a cylindrical block or housing 58 threaded at 60 and 62 to sections of the pump housing 12 so as to be arranged therein. An uppermost portion of the housing 58 is provided with an enlarged recessed portion 64 in which is disposed the valve unit 54. A portion 66 of the inner periphery of the recess 64 acts as a valve seat for the rotary valve for a purpose as will be hereinafter set forth.

A port or conduit 68 is provided in the block 48 and provides communication between the discharge outlet of the motor and housing 58, so that discharge gas from the motor is directed through the conduit 68 into the housing 58 for a purpose as will be hereinafter set forth.

The manifold or housing 58 is provided with a plurality of circumferentially spaced apertures 70 (Fig. 4) disposed immediately above the seat portion 66, and in communication with the port 68. Preferably six apertures are provided, however, it will be apparent that any practical number may be utilized. Similar ports or apertures 72 are provided in the housing 58 immediately below the seat portion 66, it being understood that each set of ports 70 and 72 are in vertical alignment with each other. Ports 72 provide communication with conduit 74 for a purpose as will be hereinafter set forth.

The valve 54 is provided with a recess or groove 76 adapted to intermittently communicate with a set of each of the ports 70 and 72 to allow communication of the discharge fluid pressure from the motor with the port 74. The operation of the valve 54 simultaneously with the rotation of the shaft 34 to intermittently place the groove 76 in alignment with a set of ports 70 and 72 allows the discharge fluid from the motor to be periodically discharged into the port 74 for a purpose as will be hereinafter set forth.

The portion 78 of the housing 58 between the sections of pump housing 12 is provided with a plurality of circumferentially spaced outlet ports 75

80 (see Figs. 1 and 3) providing communication between the interior 82 of the housing 58 and a space 84 between the housing 12 and the tubing 6. The outlet ports 80 allow discharge of oil pumped into the chamber 82 into the space 84.

In order to assist the lifting of the oil load in the space 84, the discharge gas from the rotary motor is directed into the oil stream to pneumatically aerate the column of oil upward. 10 In order to direct the discharge gas into the oil stream the conduit 74 is in communication with an annular channel 86 which in turn communicates with a plurality of vertically disposed ports 88 dividing the gas into smaller bubbles and directing it to the outlet ports 80 (see Figs. 3 and 5). Displaced oil discharging through an outlet port 80 is immediately contacted by the discharge gas from ports 88 so that the outlets 80 act as agitating or "batching" chambers where- 20 in the oil and gas is thoroughly mixed to cause a frothy mixture in the column load. The periodical or intermittent discharge of the finely divided gas directed into the outlet ports 80 provides a rapid percussive thrust of gas pressure at a definite speed to thoroughly agitate and froth the oil. It will be apparent that the discharge gas is maintained at a pressure slightly higher than the oil load so as to assist in the lifting of the oil, as fully disclosed in detail in my co-pending application mentioned supra.

The tubing portion 6 (see Figs. 1 and 2) is provided with a plurality of circumferentially spaced apertures 90 for discharging the gas and oil mixture into the space 92 between the tubing and the casing 2. It will be understood that the apertures further assist the diffusion and dissemination of the discharging bubbles of gas so that the gas is thoroughly broken up into an infinite number of small bubbles to materially increase the lift efficiency by the elimination of large coalesced volumes of gas.

Operation

Although it is thought that the operation will be apparent from the above detailed description, a brief résumé of the operation is as follows:

Input fluid such as gas or air at a sufficient pressure is discharged through the apertures 16, ball valve 30 and into the metering device (not shown) controlling the speed and volume of the actuating fluid for the motor in a definite ratio to the torque demanded of the motor shaft 34 by the pump load. The rotation of the motor blades 38 by the actuating fluid with a consequent rotation of shafts 34 and 42 causes the rotor 44 to move in an eccentric path with respect to the stator 46 of the pump. In this manner fluid in the shot hole is displaced by the pump into the area 82 to be discharged through the outlet ports 80.

The discharge gas from the rotary motor in addition to assisting the control of the metering device as disclosed in my co-pending application mentioned supra is likewise directed into the port 68 where the simultaneous rotation of the valve 54 with shaft 34 allows a periodic discharge of the motor discharge gas into the ports 74, 86 and 88. This periodic or intermittent discharging of gas through the valve unit 54, as well as the breaking up of the gas stream by the ports 88, imparts to the pumped oil high velocity concussions or vibratory shocks of finely divided gas which immediately agitates the oil to cause a frothy mixture of gas and oil. The

gas and oil mixture discharging from the outlet ports 80 into the space 84 discharges through the apertures 90 (Fig. 2) into the space 92 between the tubing 4 and the casing 2. The aperture 90 provides for a further breaking up of the gas and oil mixture to deliver the oil into the eduction tube in a condition of greatest efficiency for lifting.

In the continued operation, with an increase in pressure head or column load, the unit automatically provides an increased motor discharge pressure so as to inject an increased proportion of high pressured discharge gas into the column, and affecting an increase in speed throughout the column to reduce "slippage" or frictional resistance. Suitable packing 94 prevents discharge of the mixture into the tubing 4, while suitable packing 96 between the tubing 6 and casing 2 blocks off the pumped oil from the shot hole.

Fig. 6 is a modification showing a mixing or "batching" of the discharge motor gas and oil in the uppermost part of the unit. It will be understood that in this modification the valve unit of the preferred embodiment is preferably eliminated and exhaust gas in the motor communicates directly into the uppermost portion of the unit. The pump housing 100 comprises two cylindrical sections 101 and 102 of different diameters connected by an integral portion 104. The housing 100 is preferably disposed in spaced relation in two lowermost sections of well tubing 105 connected together by a collar 106 having a recessed portion 108. A vertically extending cylinder 110 is secured at 111 to the collar 106 and acts as a baffle for a purpose to be herein-after set forth. A cylindrical block 112 is disposed within the housing 100. A spring urged ball check valve 114 is disposed in a recessed portion 115 of the block 112. In-put fluid for actuating the motor as shown in the preferred embodiment is directed through the valve 114, a conduit 116 provided in block 112, into the interior 118 of a cylinder 120 disposed within the housing and secured in any suitable manner to the lowermost portion of the block 112. A floating screen 122 is disposed in the chamber 118 and acts to catch any debris which may be present in the in-put fluid. The floating arrangement of the screen is provided by a helical spring 124 and apertured washer 126 anchoring one end of the screen. It will be understood that the lower portion of the filter (not shown) is anchored in a manner similar to the upper portion such as the spring 124 and washer 126 in order to provide the floating arrangement of the filter 122.

The spaced relationship of the block 112 and housing portion 102 provides a chamber 124 communicating with the discharge side of the motor (not shown) thereby providing direct passage of discharge fluid pressure from the motor through chamber 124 and outlet ports 127 arranged in the uppermost portion of block 112. It will be apparent that the pump unit as shown in the preferred embodiment displaces the oil through a space 128, apertures 130 provided in the cylinder 110, hence into the chamber 122 between the housing and the tubing. A floating ring 134 is disposed on the periphery of the cylindrical block 112 above the outlet ports 127. The ring acts as a check valve for gas discharging through ports 127. The inclined portion 136 is provided with a plurality of apertures

136 and discharged gas pressure from the motor is directed through the apertures 136 causing a breaking up or dissemination of the gas into finely divided particles prior to being "batched," or mixed, with the oil present in the chamber 122. It will be apparent that the shouldered portion 138 of the baffle agitates the oil discharging through ports 130 to assist in the forming of a "frothy" mixture of gas and oil.

As illustrated in Fig. 7, the valve unit of the preferred embodiment is eliminated from the motor shaft 34a and, as in the preferred embodiment, discharge fluid pressure from the rotary motor is directed through ports 150 into a space 152 provided by cylinder 154, hence through a plurality of apertures 156. The apertures 156 break up the gas into finely divided particles prior to mixing with the displaced oil in space 160. The frothy mixture is discharged through outlet ports 162 into the eduction tube or tubing 6a.

From the foregoing it will be apparent that the invention establishes an increased efficiency for a combination pumping and "gas lifting" of oil from a well hole by the thorough mixing of a continuous stream of pumped oil with high pressured gas or air whereby the oil in the eduction tube is broken up into a minutely divided mixture of gas and oil bubbles to affect an increase in speed of the pumped mixture in the column, which in turn decreases "slippage" of oil particles due to friction. Furthermore, imparting to the gas to be injected frequency interruptions in the form of pressure percussions, in turn imparts to the pumped oil vibrations for agitating the oil and causing the forming of a frothy or emulsified gas and oil mixture whereupon the pumped load is materially decreased to affect the lifting efficiency, and at the same time provide a mixture of gas-oil saturation so that freed gas at the top of the well is afforded the greatest oil absorption, which is advantageous in the recovery of liquifiable constituents from the gas by cracking.

Changes may be made in the combination and arrangement of parts as heretofore set forth in the specification and shown in the drawings, it being understood that any modification in the precise embodiment of the invention may be made within the scope of the following claims without departing from the spirit of the invention.

What I claim is:

1. In an oil lifting apparatus comprising a gas driven motor having a shaft for driving a rotary pump, means providing communication between the discharge side of the motor and the oil being pumped, and means mounted on the motor shaft and cooperating with the communicating means to allow periodic thrusts of motor discharge gas into the oil stream to cause a frothy mixture of gas and oil.

2. In a pump mechanism, a pump unit driven by a fluid actuated motor, means providing communication between the motor and the liquid being pumped to allow motor discharge fluid to pneumatically displace the liquid, a valve actuated by the motor for causing periodic thrusts of motor discharge fluid into the liquid stream whereby the pumped liquid is agitated to form a frothy mixture of gas and oil.

3. In a pump mechanism, a pump driven by a fluid actuated motor, means providing communication between the discharge side of the motor and the liquid being pumped, a valve interposed

in the communicating means and actuated by the motor for causing a periodic flow of motor discharge fluid into the liquid stream, and means for breaking up the discharge pressure into finer particles and cooperating with the periodic fluid flow to cause agitation of the pumped liquid and form a frothy mixture of fluid and liquid.

4. In a liquid lifting apparatus comprising a cylinder disposed in the tubing of a well hole, a rotary pump arranged in the cylinder, a fluid driven motor disposed in the cylinder and having a shaft for actuating the pump, a cylindrical housing disposed in the cylinder between the motor and the pump, a recessed valve mounted on the shaft and arranged in the housing, communicating means between the discharge side of the motor and the valve, communicating means between the valve and the liquid to be pumped, a plurality of ports arranged in the housing and cooperating with the recessed valve to allow periodic discharge of motor fluid into the liquid stream.

5. In a liquid lifting apparatus comprising a cylinder disposed in the tubing of a well hole, a rotary pump arranged in the cylinder, a fluid driven motor disposed in the cylinder and having a shaft for actuating the pump, a cylindrical housing disposed in the cylinder between the motor and the pump, a recessed valve mounted on the shaft and arranged in the housing, communicating means between the discharge side of the motor and the valve, communicating means between the valve and the liquid to be pumped, a plurality of circumferentially spaced ports provided in the housing and cooperating with the recessed valve to allow periodic thrusts of motor discharge fluid into the liquid stream to cause agitation of the liquid and form a frothy oil and gas mixture.

6. In a lifting apparatus comprising a cylinder disposed in the tubing of a well hole, a rotary pump arranged in the cylinder, a fluid driven motor disposed in the cylinder and having a shaft for actuating the pump, a cylindrical housing disposed in the cylinder between the motor and the pump, a recessed valve mounted on the shaft and arranged in the housing, a conduit

providing communication between the discharge side of the motor and the valve, a second conduit providing communication between the valve and the liquid to be pumped, a plurality of ports arranged in the housing and cooperating with the recessed valve for periodically discharging the motor discharge fluid into the liquid stream to cause agitation of the pumped liquid, a plurality of small ports formed in the last mentioned conduit to break up the periodically flowing fluid into minutely divided particles to form a frothy mixture of gas and oil.

7. In a well pumping apparatus comprising a cylinder disposed in well tubing arranged in spaced relation to the casing of a well hole, a rotary pump arranged in the cylinder, a fluid driven motor disposed in the cylinder for actuating the pump, means providing communication between the discharge side of the motor and the liquid being pumped whereby discharge fluid pressure from the motor is utilized to pneumatically displace the pumped liquid, means for periodically thrusting the discharge fluid into the liquid stream, means for disseminating the discharge fluid into small bubbles prior to injection into the liquid stream, and means provided in the tubing for further diffusing the mixture discharging into the casing.

8. In a bottom hole rotary pump actuated by a fluid driven motor automatically receiving actuating fluid at a speed and volume necessary to actuate the motor for any particular torque required by the pump, means providing communication between the discharge fluid outlet of the motor and the liquid to be pumped, means interposed in the communication means for creating a periodic flow of the discharge fluid of the motor into the liquid stream, and means provided in the communicating means for disseminating the discharge fluid into smaller bubbles prior to injection into the liquid to be pumped, said last mentioned means cooperating with the periodic flow to cause agitation of the liquid to be pumped for forming a frothy mixture.

HAROLD R. DOWNS.
